JAMES MAHONY, OF NEWPORT, RHODE ISLAND.

STEAM-BOILER FURNACE.

SPECIFICATION forming part of Letters Patent No. 240,434, dated April 19, 1881.

Application filed February 23, 1881. (No model.)

To all whom it may concern:

Be it known that I, JAMES MAHONY, a citizen of the United States, residing at Newport, in the county of Newport, in the State of Rhode Island, have invented certain new and useful Improvements relating to Steam-Boiler Furnaces, of which the following is a specification.

A supply of air in small streams properly distributed within the currents of hot gases flowing from a boiler-furnace has been long known to be beneficial. It serves mainly or entirely, by supplying oxygen, to burn the combustible portions of the gases. Steam in limited quantities has also been found beneficial. It is not so easy to determine the precise manner in which it serves.

My invention affords superior means of supplying air and steam in controllable quantities at the right points in the hot currents of gases, with great facility for controlling the supply of both steam and air, and for repairing the apparatus when the parts exposed to the heat shall become cracked or otherwise defective. I introduce air and steam through apparatus provided in and connected with the bridge-wall or the parts immediately back of the furnace. The parts exposed to the full heat of the combustible gases are formed separately from the stationary parts, and may be readily exchanged. The steam admitted in small quantities serves to force in the air. Both are efficiently controlled at will.

The accompanying drawings form a part of this specification, and represent what I consider the best means of carrying out the invention.

Figure 1 is a longitudinal section on the line T T, Fig. 2. Fig. 2 is a transverse section on the line S S, Fig. 1. The remaining figures represent a modification. Fig. 3 is a longitudinal section, and Fig. 4 a transverse section.

Similar letters of reference indicate like parts in all the drawings.

I have represented the invention as applied with plain cylindrical boilers and ordinary grates and appurtenances; but it will be understood that these features, as also all the parts not here especially referred to, may be of any ordinary or suitable character.

A is the boiler; B, the grate; C, the bridge-

wall, performing its ordinary functions, extending across at the rear end of the furnaces, and C' middle walls separating the furnaces of two boilers. I have marked the interiors of 55 the furnaces b, and the flues or combustion-chambers in which the gases are burned by the aid of my apparatus b'.

M M, &c., are nearly spherical shells of fire-brick, provided with numerous small perforations, m, arranged as shown. Each of the shells has an open neck, M', the exterior of which is tapered to facilitate the production of a tight fit into a corresponding socket in the apparatus through which the air is received. These hollow shells M M' are arranged at short distances apart on the top of the bridge-wall, and exposed directly to the currents of intensely-hot gases issuing from the furnace and flowing along beneath the boiler.

G' G' are a series of sockets, of cast-iron or other suitable material, formed in the tops of a set of chambers, G, which are connected by passages F to a transverse air-duct, E. This transverse duct E receives the air through a 65 longitudinal duct, D, built in the middle wall, C'. The induction of air is controlled by a register or other ordinary or suitable valve, D'.

H is a steam-pipe communicating with the top of the boiler, and extending transversely 70 of the apparatus through the bridge-wall and through the chambers G, as represented. In the top or side of the pipe H, at about the center of each chamber G, is a small orifice, h. The flow of steam through the pipe H is controlled by a screw-valve or other valve, H'. When the steam from the boiler is allowed to flow with full force and fill the pipe H up to the boiler-pressure it issues with great force through the orifices h and blows up through 75 the corresponding neck M' into the perforated shell M, and issues through the several orifices m. If the air-valve D' is closed with approxi-

mate tightness, little besides highly-heated steam will thus issue through the orifices m 80 and mingle with the gases; but if the air-valve D' is partly or entirely open the force of the jets of steam issuing from the orifices h will draw in a large volume of air and introduce it with the steam into the combustion-chamber. 85 By closing the cock H' partially or entirely the supply of steam will be correspondingly

reduced; but in such case, if the air-valve D' is open air may flow unobstructed through the several passages and issue through the orifices *m*; but the quantity of air thus supplied will be less. The jets of steam from the orifices *h* 5 perform two functions: they supply steam to the gases, and thus act chemically to effect the conditions controlling the combustion, and they act mechanically to drag along and force out 10 through the orifices *m* with the steam a larger quantity of air than would otherwise flow.

The necks *M'* of the shells *M* are tapered on the exterior, and the sockets *G'* on the chambers *G* are correspondingly tapered. When 15 the forms are perfect they will form tight joints without luting; but under ordinary conditions I prefer to lute them by applying a thin stratum of clay wash on the interior of the socket *G'* and on the exterior of the neck *M'* before applying them together. This being done while 20 the parts are cold, and allowing it time to be thoroughly dried before any intense heat is applied, the junction is tight and will ordinarily endure as long as the shell.

25 Modifications may be made in many of the details without sacrificing the advantages of the invention. Parts of the apparatus may be used with some advantage without the others.

Figs. 3 and 4 show the arrangement where 30 only a single furnace is employed. In such case the air-duct *E* receives the air at one end or both ends, and the attendant has not the same facility for preserving the condition of the air-valve *D'* and for controlling it with convenience as in the other and preferable form. 35

The shells *M* may be made of cast-iron or other durable metal, instead of fire-brick, if preferred. The spherical form is important with any material, because it not only better allows the air and steam to jet in all directions, but 40 also because it is not as likely to crack or fail in any manner under the intense heat.

The longitudinal air-duct *D* may be made in a side wall, instead of in a middle wall, if circumstances shall require it; but I prefer to 45 place it in a middle wall, and thus allow one passage, *D*, to control the air for two furnaces.

I claim as my invention—

1. The perforated shells *M M'*, in combination with the bridge-wall *C*, sockets *G'*, chambers *G*, passages *F*, air-duct *E*, and the steam-pipe *H h* and its connections, adapted to serve 50 relatively to each other and to the furnace *b*, combustion-chamber *b'*, and boiler *A*, as and for the purposes herein specified.

2. The combination of the longitudinal air-duct *D* and controlling means *D'* in the longitudinal wall with the air-duct *E*, chambers *G*, sockets *G'*, steam-pipe *H h* and connections, and with the masonry *C C'* and boiler *A*, arranged to serve with detachable shells *M M'*, 60 as herein specified.

In testimony whereof I have hereunto set my hand at New York city, this 18th day of February, 1881, in the presence of two subscribing 65 witnesses.

JAMES MAHONY.
